UNITED STATES PATENT OFFICE.

THOMAS DALY, OF NEW YORK, N. Y.

INDICATING DEVICE.

Application filed March 18, 1924. Serial No. 700,172.

My present invention relates to indicating devices and more particularly to devices adapted to be employed in safety valises as shown and described in my copending application for the prevention and detection of the theft of bank notes, stocks, bonds, negotiable paper or other instruments as the same are conveyed from one place to another. In these safety valises provision is made when the valise is stolen or when attempts are made to open the valise by unauthorized persons for actuating devices for indicating that the contents of the valise are in unauthorized hands by mutilating the bank notes or other papers in a predetermined manner, as for example, by spraying or otherwise treating the same with a colored liquid dye or other similar substance. My present invention relates to these particular indicating devices and in carrying out the same as hereinafter more particularly described I employ a receptacle preferably comprising an outer casing and an inner casing, the inner casing being adapted to receive a suitable explosive and the outer casing a discoloring material, while both casings have substantially aligned joints which are disrupted by the explosive material when fired to create a pressure within the outer casing to expel the discoloring fluid therefrom. In carrying out the invention the explosive material is fired electrically or otherwise when the valise containing the valuable papers is unlawfully taken from the person having proper possession thereof or when attempts are made to open the valise.

In the drawing:

Fig. 1 is an end elevation of the indicating devices comprising my present invention.

Fig. 2 is a partial longitudinal section of the same.

Fig. 3 is a transverse section.

Fig. 4 is a diagrammatic plan of the electric circuits and the cartridge employed, and

Fig. 5 is a sectional elevation illustrating the application of the apparatus.

By reference to the drawings, it will be seen that in carrying out the invention I employ a receptacle preferably comprising inner and outer casings. The outer casing is indicated at 10 and is preferably cylindrical. The cylindrical wall of the outer casing is provided with a longitudinal slot 11 normally covered by a strip of thin metal 12 which is soldered or otherwise connected to the outer

surface of the casing in such a manner as to make an easily disruptable joint therewith. The ends of the cylindrical wall of the outer casing are fitted with heads 13 and 14. 60 These heads 13 and 14 are fitted respectively with rims 15 and 16 adapted to pass over the ends of the cylindrical wall so that in their normal positions the heads are sunken or set in an appreciable distance from the ends of 65 the casing. The ends of the casing are covered with caps 17 and 18 so that there is an appreciable space 19 at each end of the casing between the heads 13 and the caps 14 forming the end members thereof. The 70 cap 17 in oppositely disposed positions is provided with lugs 20, and similarly the cap 18 is provided with oppositely disposed lugs 21. The heads and the caps are maintained in position on the ends of the casing by means 75 of rods or bolts 22 and 23 which pass through and extend between the lugs on the caps 17 and 18.

The inner casing is also preferably cylindrical and of materially smaller diameter 80 than the outer casing. This inner casing is indicated at 24 and is provided with a longitudinally extending slot 25 normally covered by a strip of thin metal 26 which is secured to the outer surface of the walls of 85 the inner casing by a solder or other joint which is easily disrupted. In an oppositely disposed position the inner casing is also provided with a longitudinally disposed slot 27 which is similarly covered by a strip of 90 thin metal 28 secured to the outer surface of the walls of the inner casing by a solder or other equally disruptable joint. The inner casing extends longitudinally within the outer casing and passes through and is secured in or to the walls of the heads 13 and 14 as indicated in Fig. 2 of the drawing. 95 When the parts are in position the oppositely disposed longitudinal slots 25 and 27 in the inner casing are preferably in alignment 100 with the longitudinally disposed slot 11 in the outer casing. Passing through one end wall of the inner casing and suitably secured therein I employ a cartridge 29 having lead wires 30 and 31 extending therefrom. 105 These lead wires pass through the space 19 between the head 13 and the cap 17 of the outer casing in which there may be a filling or packing of felt or other similar material as indicated at 32 and the lead wires pass 110 out of the casing through an aperture 33 provided for this purpose in the cap 17. The

inner casing is filled with a charge of gun powder or other similar explosive material as indicated at 34, and the outer casing is filled to a predetermined extent with a quantity of liquid dye as indicated at 35, or any other equivalent discolored material.

The indicating apparatus hereinbefore described is particularly adapted for use in a valise or traveling bag of a similar nature in which bank notes, stocks, bonds or other valuable papers may be transferred from one place to another. As illustrated diagrammatically in Fig. 5 of the drawing, the walls of such a bag are indicated at 36. 15 The indicating device as illustrated may be maintained in position in the bag by hangers 37 and 38 connected at one end to a wall of the bag and provided at their other ends with hooks 39 and 40 respectively, for example for engagement with the bolts or rods 22 and 23 for supporting and normally maintaining the indicating apparatus in position in the bag. As shown in Figs. 3 and 5 of the drawing I may employ strap members 41 and 42 suitably connected to the shell of the outer casing by rivets 43, 44 or otherwise and extending in opposite directions and terminating in hooks 45 and 46. These hooks 45 and 46 form slideways for the reception of a drawer 47 or other container adapted to receive the papers to be carried in the bag. As illustrated the cover of this drawer 47 is provided with a longitudinally disposed slot 48 so placed as to be in alignment with and adjacent to the slot 11 and its cover 12 in the wall of the outer casing 10. Normally the slot 48 in the upper wall of the drawer is closed by a pivotally mounted plate 49 which is maintained in position to 30 cover the slot by means of a spring 50 or otherwise.

In order to operate the indicating device as hereinbefore described the lead wire 31 from the cartridge 29 may be connected to one terminal of a battery 51 or other suitable source of energy, while the other terminal of the battery is connected by a lead 52 to one terminal 53 of a circuit closing device and the other lead wire 30 from the cartridge 29 is connected to the other terminal 54 of this circuit closing device.

While it forms no part of my present invention the device for closing the circuit to the cartridge 29 is actuated in any suitable manner when the valise is taken surreptitiously or falls into the hands of unauthorized persons in any manner whatsoever, and also when attempts are made to open the valise except in a predetermined manner. 45 It will be understood, therefore, that when the circuit closing device is operated the circuit will be closed to the cartridge 29 to explode the same and fire the charge of gun powder 34 in the inner casing, disrupting either one or both of the joints covering the

longitudinal slots in the walls thereof and also the disruptable joint in the walls of the outer casing whereby the discolored material or other similar substance contained in the outer casing will be caused to pass either by gravity or by force or both through the slot 12 into and through the slot 48 in the upper wall of the drawer to come into contact with the papers therein to indicate that the same have been obtained in an unauthorized manner. It will now be understood that the purpose of employing the hinged plate 49 is to prevent the return of the discolored material or any appreciable part thereof from the drawer to the interior of the outer casing, the pressure under which the discolored material is caused to flow from the receptacle in which it is normally contained being sufficient to swing the plate 49 to permit the discolored material to pass in this direction but not in the other as when this pressure is relieved the spring 50 causes the plate 49 to return to its normal position. It will also be understood that the indicating device as herein shown and described is more or less diagrammatic and that other and equivalent forms thereof may be employed without departing from the nature and spirit of my invention.

I claim as my invention:

1. In a device of the class described, an outer casing having a disruptable longitudinal joint, the said outer casing being adapted to contain a liquid, an inner casing also having a disruptable longitudinal joint therein, the said inner casing being adapted to contain an explosive, and a cartridge fixed in the walls of the said inner casing.
2. In a device of the class described, an outer casing having a longitudinal slot therein, a strip normally covering the said slot and making a disruptable joint in the walls of the outer casing, the said outer casing being adapted to contain a liquid, an inner casing having a longitudinal slot therein, a strip normally covering the said longitudinal slot and forming a disruptable joint in the wall of the inner casing, the said inner casing being adapted to contain an explosive, the said slots in the outer and inner casings being in alignment with one another, and a cartridge fixed in the walls of the said inner casing.
3. In a device of the class described, an outer casing having a longitudinal slot therein, a strip normally covering the said slot and connected to the wall of the casing to form a disruptable joint therein, the said outer casing being adapted to contain a liquid, an inner casing eccentric with the outer casing and having a longitudinal slot therein, a strip normally covering the slot in the inner casing and connected to the wall thereof to form a disruptable joint therein, the said inner casing being adapted to contain

an explosive, inset head members forming the ends of the outer casing and in which the said inner casing is mounted, and a cartridge fixed in a wall of the said inner casing.

5 4. In a device of the class described, an outer casing having a longitudinal slot therein, a strip normally covering the said slot and connected to the wall of the casing to form a disruptable joint therein, the said outer 10 casing being adapted to contain a liquid, an inner casing eccentric with the outer casing and having a longitudinal slot therein, a strip normally covering the slot in the inner

casing and connected to the wall thereof to form a disruptable joint therein, the said inner casing being adapted to contain an explosive, inset head members forming the ends of the outer casing and in which the said inner casing is mounted, a cartridge fixed in a wall of the said inner casing, and caps fitting over and secured to the ends of the said outer casing.

Signed by me this 23rd day of February, 1924.

THOMAS DALY.
